UNITED STATES PATENT OFFICE

163,784

CARD ANALYZING UNIT

William Wockenfuss, Union, N. J., assignor to
Control Instrument Company, Inc., Brooklyn,
N. Y., a corporation of New York

Application November 13, 1950, Serial No. 12,940

Term of patent 14 years

(CL. D64—11)

To all whom it may concern:

Be it known that I, William Wockenfuss, a citizen of the United States, residing in Union, in the county of Union and State of New Jersey, have invented a new, original, and ornamental Design for a Card Analyzing Unit, of which the following is a specification, reference being had to the accompanying drawing, forming a part thereof.

In the drawing:

The figure is a perspective view of a card analyzing unit showing my new design, the opposite side presenting substantially the same appearance as the side shown, and the rear being plain.

What is claimed is:

The ornamental design for a card analyzing unit, as shown and described.

WILLIAM WOCKENFUSS.
